[57] CLAIM

The ornamental design for a cover for cigarette lighter, as shown and described.

DESCRIPTION

FIG. 1 is a rear view of a cover for cigarette lighter showing my new design;

FIG. 2 is a front view thereof;

FIG. 3 is a left side view thereof;

FIG. 4 is a top plan view thereof;

FIG. 5 is an underneath plan view thereof;

FIG. 6 is a top perspective view thereof; and

FIG. 7 is a right side view thereof.

The body of the cigarette lighter is shown in broken lines for illustrative purposes only.
